UNITED STATES PATENT OFFICE.

ANTHONY BERDANIER AND ADAM F. BERDANIER, OF PHILADELPHIA, PA.

STOCK-CAR.

SPECIFICATION forming part of Letters Patent No. 291,136, dated January 1, 1884.

Application filed August 16, 1883. (No model.)

To all whom it may concern:

Be it known that we, ANTHONY BERDANIER and ADAM F. BERDANIER, citizens of the United States, and residents of Philadelphia, in 5 the county of Philadelphia and State of Pennsylvania, have invented certain new and useful Improvements in Stock or Cattle Transportation-Cars, of which the following is a specification.

10 The invention relates to improvements in stock or cattle cars; and it consists in a certain novel construction and arrangement of parts, hereinafter described, and particularly pointed out in the claims, whereby cattle during transportation may be supplied with food and with 15 fresh water, the water being furnished them in a stream having a constant flow during and caused by the motion of the car-axle, with proper connecting devices.

20 The object of the invention is to provide a transportation-car in which the cattle may receive proper treatment without the constant attention of train-employés. The cruel treatment and great privations to which cattle are 25 subjected in the transportation-cars now in use are well known and have evoked popular condemnation, and to remedy the heretofore-existing objections to these cars is the purpose of the present invention.

30 Referring to the accompanying drawings, Figure 1 is a side elevation of a car embodying the elements of our invention. Fig. 2 is a plan view of the floor of same. Fig. 3 is a section through the line xx of Fig. 1, and Fig. 35 4 is a section through the line 1 2 of Fig. 1. Fig. 5 is a detached section on the line 3 4 of Fig. 1.

Similar letters of reference in the various views indicate corresponding parts.

40 A denotes the car, having a bed, B, mounted upon the wheels C, which wheels are of the usual construction, and are connected by axles D, in the customary manner.

In the floor or bed B, between the intermediate stringers, are arranged the tanks E, (four being in the present instance employed,) which extend nearly the entire length of the car, as shown, and are connected by the cross-pipe F, so that the water may flow freely into 45 all of the tanks, and from one to the other.

In the corners, at one end of the car, are

provided the vertical pipes or receptacles G, which lead to the two outside tanks E, and into which the water is poured at the proper time when the tanks are to be filled.

55 At each side and at one end of the car is the trough H, which will be secured at a suitable height to permit the cattle to drink from it, and may, for convenience, be supplied with a hinged cover, I.

At one end of the car, and above the axle, is provided a pump, J, consisting of the cylinder K, its rod L, and the rocking lever M, for operating the same, the outer end of the rocking lever being connected by the rod N 65 and knuckle-strap O with the eccentric P, rigidly secured upon the car-axle. A pipe, Q, leads from the tank E to the base of the pump-cylinder, and from the upper part of same a pipe, R, passes to the trough H. The 70 operation of this part of our invention is as follows: The tanks having been filled with water and the car set in motion, the revolving eccentric P imparts a vertical reciprocating motion to the rod N, thereby actuating the rocking lever M and operating the pump J. The 75 effect of this arrangement is that while the car is in motion the pump J will draw the water from the tanks E through the pipe Q and discharge it into the trough H through 80 the pipe R. This movement of the water is continued while the car is in motion, and to prevent the trough H from overflowing suitable return-pipes S are provided, through which the water may pass to the tanks E. The tanks 85 E may be provided with a suitable outlet, T, whereby they may be emptied when it is desired.

90 Adjacent to the door of the car V, we have provided the trough H with an adjustable section, W, as indicated in the drawings, so as to permit the door to be opened and the cattle to enter or pass from the car. The adjustable section will be hinged at X, and is adapted, by means of the lever Y, to be turned upward 95 into about a vertical position. The ends of the adjustable section W will be closed, and the water will find its passage to it by means of the removable pipe Z, which passes from the under side of the trough proper to a suitable joint on the under side of the section. There will be one section of the removable pipe 100

Z at each end of the section *W*. The door of the car *V* is provided with a flat bolt or projecting piece, *a*, which comes in contact with the lever *Y*, and when the door is opened this bolt acts to draw the right-hand end of the lever upward, carrying the section *W*, as indicated in the drawings. The closing of the door *V* operates to lower the lever *Y*, and with it the section *W*.

10. Another part of my invention relates to the feed-racks *b*, arranged at the upper part of the car. They consist of wire frames secured at their ends in strips of wood or metal *c*.

On the center of the car is provided the 15 hanger *d*, for supporting the central part of the racks *b*.

Upon the sides of the car are provided swinging doors *e*, provided with a proper catch, and by means of which doors hay, grain, &c., may 20 be placed upon the racks *b*. Adjacent to the door *V* the racks are made movable, in order that when the door is opened on either side of the car the rack may be elevated, so as to clear the passage. These removable sections consist of wires and the strips *c*, the central part 25 of the wires being rested in hangers *d* and arranged so as to pass each other. Suitable levers, *f*, are provided for the purpose of operating these movable sections of the grain-rack.

30 The car will be provided with suitable stall-bars, *i*. We do not limit ourselves to the exact construction illustrated, but reserve the right to modify the same in minor details as we may 35 see fit within the scope of this invention.

What we claim as our invention, and desire to secure by Letters Patent, is—

1. A stock-car provided in its floor with water-tanks and within the car with a water-45 ing-trough, overflow-pipes connecting the trough and tanks, and a pump, the pump being actuated by the movement of the car to

draw the water from the tanks and discharge it into the trough, whereby and by means of the overflow-pipes a continuous current of the 45 water is provided during the movement of the car, substantially as set forth.

2. The combination, in a car, of the tanks *E*, pump *J*, pipes *Q R*, trough *H*, and overflow-pipes *S*, connecting the trough and tanks, 50 the whole being arranged and adapted to operate substantially as set forth.

3. In a stock-car, the trough *H*, provided with the section *W*, hinged at one end, and supplied with detachable connecting pipe or 55 hose *Z*, and adapted to have one of its ends elevated, as specified, by the opening of the car-door, substantially as set forth.

4. The trough *H*, provided with the section *W*, lever *Y*, and detachable pipes, substantially as set forth.

5. The combination, in a car, of the tanks *E*, pump *J*, pipes *Q R*, trough *H*, overflow-pipes *S*, the pump-operating rod *N*, and eccentric *P*, substantially as set forth.

6. In a stock-car having doors *e*, the grain-racks consisting of the bent rods *b*, connecting-bars *c*, and hangers *d*, those portions of the racks on each side of the car opposite to the car-doors being independently adjustable, substantially as specified.

7. The combination, in a car, of the tanks *E*, receptacles *G*, trough *H*, pump *J*, pipes *Q R*, and overflow-pipes *S*, connecting the trough and tanks, the pump being actuated by the 75 movement of the car, substantially as set forth.

Signed at Philadelphia, in the county of Philadelphia and State of Pennsylvania, this 24th day of July, A. D. 1883.

ANTHONY BERDANIER.
ADAM F. BERDANIER.
